ANTIRATTLING DEVICE

John B. Benson, Pittsfield, Mass.

Application November 2, 1938, Serial No. 238,328

2 Claims. (Cl. 292—16)

This invention relates to improvements in an antirattling device for windows and the like.

It is an object of this invention to provide a novel device which may be positioned in the frame or sash of a window or the like and is of such construction as to effectually eliminate rattling of the windows.

It is another object to provide a device which may be inserted in a window frame or a window sash or the like in such a way that it will not only be invisible to the ordinary observer, but also out of reach to him as well, it being sunk into and within the window frame or sash.

A still further object of my invention is to provide a unique device of the character referred to which includes a casing having a movable member associated therewith which is adapted to prevent the window with which the device is associated from rattling while still permitting the window to be movably adjusted as may be desired. As a special feature, the device is adapted to obviate the need for pulleys and weights now commonly employed.

A still further object is to provide an improved antirattling device which may be made more economically and with fewer operations, both with respect to the manufacture of the parts as well as in assembling thereof, than prior devices known in the art. As special features, the parts, once assembled, cannot be readily separated from each other, either accidentally or otherwise.

Devices heretofore known all have the common objection that, in order to operate them, buffer members in the form of rollers have to be used, which members, while they may serve to prevent the window from rattling, nevertheless do not always effectively prevent undesirable vertical movements of the windows relative to their sashes.

Accordingly, I have devised novel means whereby these difficulties are overcome and I accomplish this by the provision of a device which obviates the need for buffer members in the form of rollers.

Various other novel features and advantages and other objects of my invention will be herein-after more fully described and referred to in connection with the accompanying drawing, wherein:

Fig. 1 is a longitudinal sectional elevational view of the device of the invention, partially broken away to show certain features thereof;

Fig. 2 is a front elevational view of the device shown in Fig. 1;

Fig. 3 is a perspective view of the device shown in Fig. 1;

Fig. 4 is a longitudinal sectional elevational view of a modified form of the device of the invention;

Fig. 5 is a front elevational view of the device shown in Fig. 4, partially broken away to show certain features thereof;

Fig. 6 is a perspective view of the device shown in Fig. 4; and

Fig. 7 is a cross-sectional view of the device of the invention in association with a window frame and a window stop.

Referring to the drawing more in detail, the invention will now be described. Like numerals refer to like parts in different figures of the drawing.

A body member or casing, generally designated by 10 and more or less box-like in shape, is adapted to be positioned within the frame or sash of a window.

For purposes of convenience in description, the invention will be described with respect to the device confined within the sash S rather than the frame F as shown in Fig. 7.

Fitted within the box 10 is what I call a plate or cover member 12. This is adapted to move inwardly and outwardly within the confines of the receptacle 10.

The said plate member 12 has inwardly extending ears such as 14 on the sides thereof to facilitate guided movements thereof. It also is formed to have an outwardly extending or raised portion 16 intermediate its ends which forms a projection substantially as shown.

It will be noted that according to the form shown in Fig. 1 to 3 inc., this projection has a flat forward surface. This is intended to frictionally engage the window frame for purposes as will hereinafter be made more clear.

Hollow guide members 18 are disposed within the receptacle 10 and have their inner ends secured to the bottom wall of the same in some manner, as by means of portions 20 of the guides being turned over so as to make heads. These guides 18 extend through suitable openings in the plate member 12 and they may have their outer ends also turned over so as to form heads or stops as shown for limiting the outward movement of the plate member.

Preferably the guides are formed to have countersink portions 22. These are for receiving the heads of screws which may extend through the bores of the guides for fastening the device to the window.

It will be understood, however, that such screws or fastenings are not always necessary inasmuch as the device, when inset in a recess in a window sash or frame in the manner as shown in Fig. 7, 5 cannot possibly be removed when the sash and frame are in assembled relation.

Surrounding the guide members 18 are coil springs 24 which will have their inner ends engaging the inside of the bottom wall of the receptacle 10 and their opposite ends engaging the underside of the closure member 12 substantially as shown. The springs 24 tend to urge the plate member 12 outwardly away from the bottom wall of the receptacle.

15 The arrangement is preferably such that the plate member 10 is prevented from moving outwardly beyond a point where the surfaces of its opposite end portions are flush with the top edges of the side walls of the receptacle as shown in 20 Fig. 1.

In the modification shown in Figs. 4 to 5 inc., the same general structure is shown. However, according to this form the opposite side walls of the receptacle 10' are provided with aligned openings, through one of which the body part of a 25 friction member 30 extends.

A post or stud 32 extends from the inside of the friction member to and through the opening in the opposite wall of the receptacle. The outer 30 end of post 32 may have a turned-over head part 34 as shown.

A coil spring 36 disposed within the casing surrounds the post 32 and is arranged to urge the friction member outwardly to the position shown 35 in Fig. 5. Flanges may be provided on the inside of the member 30 as shown to limit the outward movements of the same.

It will be noted that the post 32 is located between guides 18' and at right angles thereto. 40 Preferably the plate member 12 is a unitary piece of metal, that is bent intermediate its ends to have coplanar opposite end portions and the intermediate projection 16'.

In operation, when the friction member 30 is urged inwardly against the compression of the 45 spring 36, the post 32 is likewise moved so as to project outwardly beyond the said opposite side wall of the casing.

The structure of the device having been 50 explained, the installation of the above device will now be described.

The device of the invention as shown in Figs. 4-6 inc. is shown in Fig. 7 as being secured to a window sash 40 containing a pane 42. It will be 55 understood that the device may likewise be turned around and secured to the frame F or parts thereof.

To install the device, the window sash 40 is recessed, as shown, to receive the same. As 60 stated above, screws or the like are receivable through the hollow guides and the countersinks 22' make a perfectly flat surface for engaging the recess.

The raised portion 16' extends outwardly to 65 yieldingly engage the stile of the window frame as shown. On the other hand the member 30 yieldingly engages the window stop or bead 44.

It will be observed that the frictional surfaces, such as 16, 16' and 30 are relatively flat and have 70 great areas. These areas being sufficiently large

are able to frictionally engage the portion of the window frame, sash or stop which they abut and to insure against undesirable vertical movements. By means of properly tensioned springs, window cords, pulleys and sash weights can be entirely 5 eliminated and the windows can be effectively secured in any desired position.

Furthermore, the window sashes are secured in their respective frames in such a manner, by virtue of these devices, that all rattling is effectively eliminated. There is the further consideration that a tight joint is guaranteed so that cold wind and other undesirable elements are not able to gain admission through the tightly sealed joint. As shown in Fig. 7 the sash is yieldingly 15 urged against stop or bead 44 by means of spring pressed member 30.

While I have described the invention in great detail and with respect to the present preferred form thereof, it is not desired to be limited thereto since changes and modifications may be made therein without departing from the spirit and scope of the invention. What it is desired to claim and secure by Letters Patent of the United States is:

1. A unitary antirattling device for the sash and frame of a window or the like comprising in combination, a single sheet of metal having relatively angularly disposed bottom wall, side and end wall members forming a receptacle open at its upper end, guides fixed to and extending upwardly from said bottom wall within said receptacle having stops at their upper ends, a plate closing the open upper end of said receptacle having depending ears slidably engageable with inner faces of said side wall members and provided with openings slidably receiving said guides whereby said plate is movable towards and away from said bottom wall and is limited in its movement away from said plate by said stops, and springs on said guides urging said plate away from said bottom wall, said plate having a substantially flat intermediate portion in a plane spaced from the main body thereof to provide a frictional surface for engaging a part of a window. 45

2. A unitary antirattling device for the sash and frame of a window or the like comprising in combination, a single sheet of metal having relatively angularly disposed bottom wall, side and end wall members forming a receptacle open at its upper end, guides fixed to and extending upwardly from said bottom wall within said receptacle having stops at their upper ends, a plate closing the open upper end of said receptacle having depending ears slidably engageable with inner faces of said side wall members and provided with openings slidably receiving said guides whereby said plate is movable towards and away from said bottom wall and is limited in its movement away from said plate by said stops, and springs on said guides urging said plate away from said bottom wall, said plate having a substantially flat intermediate portion in a plane spaced from the main body thereof to provide a frictional surface for engaging a part of a window, said guide members having longitudinal openings therethrough for receiving screws for securing the device to a frame or sash parts of a window. 60
